Patented Feb. 24, 1920.

UNITED STATES PATENT OFFICE

CALEB E. SUMMERS, OF HUTCHINSON, KANSAS.

CARBURETER DEVICE.

1,331,856.

Specification of Letters Patent.

Patented Feb. 24, 1920.

Application filed January 2, 1917. Serial No. 140,061.

To all whom it may concern:

Be it known that I, CALEB E. SUMMERS, a citizen of the United States, residing at Hutchinson, in the county of Reno and State 5 of Kansas, have invented a certain new and useful Improvement in Carbureter Devices, of which the following is a full, clear, concise, and exact description, reference being had to the accompanying drawings, forming 10 a part of this specification.

My invention relates to carbureter devices, and especially to devices which generally considered may be regarded as primers, that is devices adapted for use in connection with 15 or as a part of a carbureter device and constructed to exercise some function or bring about some result in addition to the usual carbureter action.

The principal object of my invention is to 20 provide a simple, practical and efficient primer or auxiliary mechanism adapted to exert a heating effect upon the liquid fuel supplied to the combustion engine, so that in cold weather the liquid fuel may be heated 25 as desired, but more especially at the time of starting the engine.

A further object is to arrange for the ready control of this primer device, so that the heating effect may be varied as desired, 30 both as to amount and as to time of its application.

A further object is to simplify the construction and reduce the cost of manufacture and make the device compact so as to 35 avoid undesirable enlargement of the engine parts.

A further object is to arrange so that this primer mechanism may be used only at pre-determined times, as for example when the 40 engine starter is in use.

In the accompanying drawings Figure 1 is a perspective view of an internal combustion engine, such for example, as is in use upon a commercial type of automobile of the 45 present day, together with a carbureter and a primer mechanism involving my present invention;

Fig. 2 is a view partly in elevation and partly in vertical section of such primer mechanism;

Fig. 3 is an end view of the same; and

Fig. 4 is a view of a detail of construction.

Referring first to Fig. 1, A represents an internal combustion engine arrangement,

such, for example as an automobile engine of the present commercial type. A carbureter 2 is shown mounted on one side of this engine structure, through the medium of a pipe 2 which is the mixture intake pipe or conduit for the engine, and a mixing chamber 3 which forms part of the carbureter 1. A liquid fuel supply pipe 4 is shown connected with the lower portion 5 of the carbureter 1, which portion 5 is the usual fluid chamber of the carbureter. It will be understood that the carbureter 5 is a commercial type of carbureter in connection with which my invention may be used. It will be understood, of course, that the invention is not limited to use with any particular type of carbureter, but may be used with various kinds of the same.

Referring to Figs. 2, 3 and 4, the auxiliary or primer mechanism involving my invention which is shown in these figures comprises preferably a tubular member 7 of substantially cylindrical form, having a side extension or wing 8, preferably made integral therewith. This side member 8 has an aperture 9 and is adapted to be inserted between the engine intake pipe 2 and the engine as shown in Fig. 1, so that the aperture 9 corresponds with the interior bore of said pipe 2. Small apertures are also provided in the wing member 8, through which bolts 10 may be passed to bolt the structure firmly to the engine member A. The tubular member 7 is connected with a pipe 11 which extends from the lower end of said member to the fluid chamber 5 of the carbureter, whereby liquid fuel may pass from said chamber 5 through the pipe or tube 11 and upwardly into the interior of said member 7. A chamber 12 is located at the lower end portion of said member 7, said chamber being in communication with the pipe 11 whereby fuel from the latter will pass into the chamber 12. A coil of wire 13 is also arranged within the chamber 12, one end of said coil having a connection (not shown) with the metallic body part of the member 7, the other end 14 of said coil being connected to a metallic rod or stem 15 which extends upwardly into and through a valve 16 which is located and arranged for longitudinal movement within the upper portion of said member 7. A chamber 17 is located above the chamber 12 and below the lower end of the

valve 16 whereby fuel coming upwardly through the chamber 12 passes into the chamber 17. An air inlet pipe 18 is arranged in one side of the member 7, affording communication between the outside air and the intermediate chamber 17. Passages or ducts 19-19 extend laterally in the member 7 and wing 8, affording communication between the interior of the chamber for the 5 valve 16 and the opening 9, whereby fuel and air passing into the chamber 7 may when said valve 16 is open, pass through the ducts 19, into the aperture 9, and thus into the bore or conduit formed by the pipe 2. 10 The valve 16 has a centrally arranged portion 20 of insulating material which insulates the connecting wire or rod 15. The coil 13 is also surrounded by an insulating member 21 of cylindric form, said member 15 20 forming the chamber 12. On the upper end of the valve 16 is located a metallic contact or terminal 22 and this cooperates with a contact spring 23 mounted above said contact 22 and conveniently held in position by 25 a laterally extending arm 24 on a bracket 25 which is secured, as by screws 26, to the upper portion of the tubular member 7. (Fig. 3). Thus it will be seen that the longitudinal movement of the valve 16 not only 30 opens and closes the side ports or passages 19, but also makes connection between the contacts 22 and 23, and thereby makes and breaks a circuit connection with the coil 13.

For effecting this longitudinal movement 35 of the valve 16, I show as a convenient arrangement a cam 28 carried by the upper end of said valve 16 and a cam groove 29 formed by cam projections 30 and 31 on the bracket 25, so that the rotary movement of 40 said valve will effect its longitudinal adjustment. A laterally projecting side arm 32 is shown connected with the upper end of the valve 16, being preferably made integral with the cam 28, and a rod 34 is 45 shown (Fig. 1), connected with said arm 32 and extending from the same to some convenient position, as for example, to the dashboard of the automobile, so that the longitudinal movement of said rod 34 will effect 50 a rotary movement of said valve and thereby cause a longitudinal adjustment of the same.

It will now be evident that the device 55 may be put into operation by such a movement of the rod 34 as will cause the valve 16 to move upwardly and thereby open the ports 19 and at the same time connect the coil 13 in circuit by effecting contact between the terminals 22 and 23. When this 60 is done the coil 13 will be energized or heated so that liquid fuel rising in the pipe 11 and passing through the chamber 12 will be heated and by passing through the chamber 17 and ducts 19 and into the engine 65 manifold will be supplied to the engine cyl-

inders in a heated condition. At the same time air will enter the passage 18 and will become mixed with the fuel in the chamber 17, and thus pass with it into the ducts 19 and engine cylinders, thus affording the engine a heated mixture. This movement of the liquid fuel and air is caused by the suction or partial vacuum formed in the engine manifold and pipe 2 by the operation of the engine, it being seen that this will occur 70 when the engine is started by external sources, as for example, by a hand crank or by an engine starter forming part of the automobile equipment. Thus during the starting operation of the engine this heated 75 mixture will be supplied to the cylinders, and this will prove very advantageous when the engine is cool, as during winter weather. At the same time more or less fuel will be supplied by the carburetor 3, the relative 80 amount supplied by the priming mechanism and the carburetor being varied according to the extent to which the valve 16 is opened. The extent to which the fuel 85 may be heated by the coil 13 may be controlled by suitable control of the amount of current passing through said coil.

As a matter of further improvement I provide an arrangement by which this priming mechanism may be used only when the 90 starting mechanism of the automobile is in use. This may be adopted or not as desired, but has the advantage that the heating coil 13 cannot be energized except when the starting mechanism is running and consequently cannot be overheated or burned out at other times, either by accident or carelessness. This arrangement consists in providing circuit connections controllable by the starting mechanism, as for example, by 95 extending a circuit wire 35 from the screw 36 connected with the spring contact 23 to a terminal or contact 37 cooperating with a contact 38 and insulating strip 39 on a rod 40 which is understood to be the rod or connection of the starting mechanism, operated to throw said mechanism into and out of operation. Another contact 41 is shown 100 cooperating with the contact 38 and insulation 39, and the connection 42 between said 105 contact 41 and a battery 43. Thus the actuation of the rod 40 either makes or breaks the circuit leading to the priming mechanism heating coil 13, so that when said circuit is closed, said heating coil may be 110 energized, but when said circuit is open, said heating coil may not be energized, and consequently cannot be heated, even though the rod 40 be actuated so as to open the valve 11 and close the contacts 22 and 23.

The introduction of air through the inlet 118 is very advantageous inasmuch as it sprays or atomizes the fuel and so prevents the fuel from having large globules, which of course are objectionable.

It will be understood that changes and modifications may be made without departing from the spirit of the invention.

What I claim as my invention is:

- 5 1. The combination with a carbureter device of a priming device comprising means for delivering a supplemental amount of fuel to be mixed with the fuel from the carbureter, means for heating said supplemental amount of fuel, and an air inlet supplying air to be mixed with said supplemental fuel before the same becomes mixed with the carbureter fuel. 70
- 10 2. The combination with a carbureter device, of a priming device comprising means for delivering a supplemental amount of fuel, an air inlet, and a valve controlling both the discharge of said supplemental fuel and also the passage of air through said inlet. 75
- 15 3. The combination with a carbureter device, of a priming device comprising means for delivering a supplemental amount of fuel, an air inlet, a valve controlling both the discharge of said supplemental fuel and also the passage of air through said inlet, and means for heating said supplemental fuel. 80
- 20 4. The combination with an internal combustion engine, of a carbureter therefor, a priming mechanism associated with said carbureter, said priming mechanism having a chamber for receiving liquid fuel, an electrically operated heating device located in said chamber, passages from said chamber for conveying heated fuel therefrom for use in the engine, a valve controlling said passages and means whereby the operation of said valve controls said electrical heating device. 85
- 25 5. The combination with an internal combustion engine, of a carbureter therefor, a priming mechanism associated with said carbureter, said priming mechanism having a chamber for receiving liquid fuel, an electrically operated heating device located in said chamber, passages from said chamber for conveying heated fuel therefrom for use in the engine, a valve controlling said passages, means whereby the operation of said valve controls said electrical heating device, and an air passage for admitting air to be mixed with said heated fuel. 90
- 30 6. The combination with the mixture inlet pipe for an internal combustion engine, of a priming mechanism having means for connection with said pipe comprising a member adapted to be fitted to the end of said pipe and having an aperture corresponding with the bore of said pipe, said priming mechanism also having a tubular member provided with a liquid fuel chamber and passages leading therefrom to said aperture in said member, and a heating device located in said fuel chamber. 95
- 35 7. The combination with the mixture inlet pipe for an internal combustion engine, of a priming mechanism having means for connection with said pipe comprising a member adapted to be fitted to the end of said pipe and having an aperture corresponding with the bore of said pipe, said priming mechanism also having a tubular member provided with a liquid fuel chamber and passages leading therefrom to said aperture in said member, a heating device located in said fuel chamber, and a valve controlling said passages. 100
- 40 8. The combination with the mixture inlet pipe for an internal combustion engine, of a priming mechanism having means for connection with said pipe comprising a member adapted to be fitted to the end of said pipe and having an aperture corresponding with the bore of said pipe, said priming mechanism also having a tubular member provided with a liquid fuel chamber and passages leading therefrom to said aperture in said member, a heating device located in said fuel chamber, a valve controlling said passages, and means whereby said valve and heating device may be simultaneously controlled. 105
- 45 9. A priming mechanism comprising a tubular member 7 having a lateral extension 8, said tubular member being provided with a liquid fuel chamber 12 containing a heating device, said members 7 and 8 being provided with a passage 19 by which fuel heated in said chamber 12 may escape for use in the engine. 110
- 50 10. A priming mechanism comprising a tubular member 7 having a lateral extension 8, said tubular member being provided with a liquid fuel chamber 12 containing a heating device, said members 7 and 8 being provided with a passage 19 by which fuel heated in said chamber 12 may escape for use in the engine, and a valve controlling said outlet passage 19. 115
- 55 11. A priming mechanism comprising a tubular member 7 having a lateral extension 8, said tubular member being provided with a liquid fuel chamber 12 containing a heating device, said members 7 and 8 being provided with a passage 19 by which fuel heated in said chamber 12 may escape for use in the engine, a valve controlling said outlet passage 19, and an air supply duct for admitting air to be mixed with fuel heated in the chamber 12. 120
- 60 12. A priming mechanism comprising a tubular member 7 having a lateral extension 8, said tubular member being provided with a liquid fuel chamber 12 containing a heating device, said members 7 and 8 being provided with a passage 19 by which fuel heated in said chamber 12 may escape for use in the engine, a valve controlling said outlet passage 19, an air supply duct for 125
- 65 13. A priming mechanism comprising a tubular member 7 having a lateral extension 8, said tubular member being provided with a liquid fuel chamber 12 containing a heating device, said members 7 and 8 being provided with a passage 19 by which fuel heated in said chamber 12 may escape for use in the engine, a valve controlling said outlet passage 19, an air supply duct for 130

- admitting air to be mixed with fuel heated in the chamber 12, and means whereby said valve and heating device may be simultaneously controlled.
5. 13. A priming mechanism comprising a tubular member 7 and a laterally extending member 8, the member 7 being provided at its lower end with a fuel chamber 12 containing an electrical heating device, a valve controlling the outlet of heated fuel from said chamber, said valve being longitudinally adjustable, and means whereby said valve may be actuated to produce longitudinal adjustment and also to control the actuation of said electrical heating device.
10. 14. A priming mechanism comprising a tubular member 7 and a laterally extending member 8, the member 7 being provided at its lower end with a fuel chamber 12 containing an electrical heating device, a valve controlling the outlet of heated fuel from said chamber, said valve being longitudinally adjustable, means whereby said valve may be actuated to produce longitudinal adjustment and also to control the actuation of said electrical heating device, and an air inlet for supplying air to be mixed with the heated fuel.
15. 15. A priming mechanism comprising a tubular member 7 and a laterally extending member 8, the member 7 being provided at its lower end with a fuel chamber 12 containing a heat coil 13, a valve located in the upper portion of said tubular member, a chamber 17 between the fuel chamber and said valve, said valve controlling the outlet of fuel from said chamber 17, an air passage 18 affording communication between the outside air and the chamber 17, ducts 19 affording an outlet from the chamber 17 when the valve is open, said ducts 19 being extended in the lateral member 8, a connecting wire in said valve, said wire being connected with the upper end of said heat coil and extended to the top of the valve 14 and there provided with a contact terminal 22, a cam carried by the upper end of the valve, cam guides on a bracket 25 secured to said tubular member 7, and a spring contact 23 secured to the upper end of the bracket 25 and arranged to operate with the contact terminal 22.
16. The combination of a carburetor, a primer, a starting mechanism, and means whereby the operation of the starting mechanism controls the operation of the priming mechanism, making said priming mechanism inoperative when the starting mechanism is not in use and operative when said starting mechanism is in use, said means consisting of a heating coil in the primer and means for connecting and disconnecting said heating coil in circuit.
17. The combination of a carburetor and a primer, said primer having a fuel chamber provided with a heating coil, an air passage for supplying air to be mixed with the fuel heated in said chamber, a passage for conveying the mixture of air and heated fuel to be mixed with the carburetor fuel, and a valve controlling said last mentioned passage.
18. A primer provided with a heating device, and also provided with an air inlet for admitting air to be mixed with fuel heated by said heating device, a passage for controlling the delivery of the mixture of air and heated fuel, and a valve controlling said passage.
- In witness whereof I hereunto subscribe my name this 16th day of December, A. D. 1916.
